UNITED STATES PATENT OFFICE.

CARL J. RENZ, OF NEW YORK, N. Y.

FOUNTAIN-PEN.

SPECIFICATION forming part of Letters Patent No. 564,842, dated July 28, 1896.

Application filed March 12, 1896. Serial No. 582,867. (No model.)

To all whom it may concern:

Be it known that I, CARL J. RENZ, of New York city, in the county and State of New York, have invented a new and Improved 5 Fountain-Pen, of which the following is a full, clear, and exact description.

The object of my invention is to provide a fountain-pen so constructed that it will write to the last drop of ink, without danger of leaking, and in which the flow of ink can be easily 10 and instantly regulated to suit the writer, or stopped entirely, enabling the pen to be carried point down in the pocket with absolute safety.

15 A further object of the invention is to construct a pen having the advantages above set forth in an exceedingly simple, durable, and economic manner, and, furthermore, to provide means whereby should the ink at the 20 pen-point or adjacent to the same become in any manner dry the flow of ink may be instantly started the moment that the pen is placed in position to write.

The invention consists in the novel construction and combination of the several parts, as will be hereinafter fully set forth, 25 and pointed out in the claims.

Reference is to be had to the accompanying drawings, forming a part of this specification, 30 in which similar characters of reference indicate corresponding parts in all the figures.

Figure 1 is a side elevation of the pen closed. Fig. 2 is a side elevation of the pen, the point being uncapped. Fig. 3 is a longitudinal 35 vertical section through the major portion of the pen, the feeder being in position to admit the writing fluid to the point of the pen. Fig. 4 is a longitudinal section through the pen in its entirety, illustrating the feeder in 40 position to close communication between the ink-chamber and point of the pen. Fig. 5 is a transverse section taken, practically, on the line 5 5 of Fig. 4. Fig. 6 is a similar section taken on the line 6 6 of Fig. 4. Fig. 7 is a 45 transverse section taken on the line 7 7 of Fig. 4. Fig. 8 is a plan view of the feeder removed from the pen. Fig. 9 is a bottom plan view 50 of the aforesaid feeder; and Fig. 10 is a longitudinal section through the feeder, taken practically at a central point.

In carrying out the invention a barrel A is constructed of suitable size, adapted as a res-

ervoir for the ink, and the said barrel at its upper end is closed by a cap B, which is held in the barrel by frictional contact, or through 55 the medium of screw-threads, as illustrated, and the cap B is preferably provided with an air-vent 10, as shown in Fig. 4, the barrel being filled with ink upon the removal of the aforesaid cap.

60 A plug C is either screwed into the lower end of the barrel or held liquid-tight therein by frictional contact, and the said plug is hollow and is provided between its ends with an exterior collar 11, serrated or otherwise 65 roughened to facilitate the removal of the plug from the barrel of the pen. The bore of the said plug is reduced at its upper or inner end, forming a vent-opening 12^a, and at its outer end the plug is preferably interiorly 70 threaded to receive a nozzle D, exteriorly threaded to meet the threads of the plug; but the nozzle and plug may be connected in a fluid-tight manner by frictional contact, if so desired. When the plug is secured in the 75 barrel, the collar 11 of the same will engage with the bottom portion of the barrel, as shown in Figs. 3 and 4.

The fountain-pen is provided with a feeder E and a nib or pen E', the nib or pen E' being 80 adapted to be introduced into the nozzle D, the said nozzle being tubular, and the feeder E is adapted for engagement with the pen or nib and is of such length that it will extend through the nozzle and through the 85 plug C into the ink-receiving chamber of the barrel A, as shown in both Figs. 3 and 4.

The feeder E comprises a body e, a shank e', and a head e², the latter being at the inner extremity of the shank. The shank is 90 circular in cross-section, as is likewise the body e, but the aforesaid body is of greater diameter than the shank and is made to taper in direction of its outer end. The point 12 of the body of the feeder is flattened upon its 95 under face and is of less thickness than the remaining portion of the body, as shown in Figs. 9 and 10. The point 12 has a number of perforations 13 made therein, and is provided upon its upper face with a series of 100 grooves 14, extending longitudinally of the aforesaid feeder, the grooved portion of the point being adapted to be brought substantially in close contact with the under face of

the nib or pen E'. The perforations 13 constitute air-passages, by means of which the ink is forced to the elevated or ribbed surface of the top of the point of the feeder formed by the grooves 14, and the ink will be compelled to flow on both sides of the point of the feeder at the top to the extremity of the same, ready for distribution through the medium of the nib or pen E'.

10 The body portion e of the feeder has a series of basins 15 made therein transversely at the top and bottom, the bottom basins being immediately below the top basins, and each top and bottom basin is connected through the medium of an opening or aperture 16, as is best shown in Fig. 10. These basins serve as reservoirs for the ink, and the ink is retained in the said basins air-bound by the aforesaid openings or perforations 16, being withdrawn by suction due to opening or closing the pen-point when the pen is to be used, since, as shown in Fig. 4, the feeder is held firmly yet removably in the nozzle D, and by screwing the nozzle upwardly the head of the feeder will be carried in direction of or away from the vent-opening 12^a in the plug, through which the shank of the feeder is loosely passed. When the feeder is drawn outward from the barrel, a washer 17, attached to the shank of the feeder at the head, will be brought more or less closely against the inner end of the plug C, regulating the supply of ink from the reservoir of the barrel to the feeder, and when the said washer 30 is brought in close engagement with the plug C, as shown in Fig. 4, the supply of ink to the feeder will be entirely cut off, so that the pen may be carried point downward, or carelessly handled with impunity, yet there will 35 be sufficient ink air-bound in the basins 15 to admit of a letter of ordinary length being conveniently written without a further supply, and the ink in the basins being air-bound will not flow to the pen-point unless the said 40 point is pressed upon the paper upon which the letter is to be written.

At each side of the feeder a groove 18 is preferably made, which serves to admit air to the feeder and facilitate the flow of ink along the same to its point, and, if in practice it is found desirable, near the inner end of the body of the feeder an annular basin 19 may be formed, and an opening 20 is then made in this basin, extending from top to bottom 50 of the feeder. While in the drawings the shank e' of the feeder is shown as provided with a spiral groove 21, the said groove may be omitted if in practice it is found desirable and simply a channel 22 formed in the inner 55 end of the body of the feeder to admit of the writing fluid being conducted to the basins of the said feeder.

The pen or nib E' is insured a proper position upon the feeder by reason of the inner 60 end of the pen or nib being brought in engagement with a saddle 23, formed upon the

upper face of the said feeder, as is particularly shown in Fig. 4, and a loose collar 24 is mounted upon the shank e' of the feeder, and the said collar will be contained within the 70 plug C, so that when the pen is brought to writing position the collar in sliding along the shank will force the ink contained in the basins 15 to the point of the pen in the event that the ink should become dried and will 75 not flow of itself to such point, and, if a single downward movement of the pen is not sufficient to accomplish this result, on moving the pen quickly forward and backward the collar will accomplish said result. 80

It is evident that, by reason of the adjustment of the feeder to and from the barrel of the pen, the ink may be made to flow more or less freely to the point or nib of the pen and that the supply of ink may be entirely cut 85 off when desired, thus enabling the pen to be carried point down without danger of spilling any of the ink that may remain between the barrel and the nib, owing to the ink in the various basins 15 being air-bound until 90 forced to flow to the point of the pen either by the action of the sliding collar 24 or by the flexing of the nib of the pen.

The longitudinal air-vents 18 are not at the exact center of the feeder, being rather below 95 the center, and connect with the lower basins, whereby the air-pressure serves to force the ink upward into the upper set of basins. The sliding collar 24 may be dispensed with, if so desired, although it is preferably used, and 100 in such event the body section of the feeder will be made much larger than illustrated.

Having thus described my invention, I claim as new and desire to secure by Letters Patent—

105

1. In a fountain-pen, a feeder provided on its under side with cavities, a longitudinal groove on each side connecting said cavities, and passages for conducting the ink from the lower to the upper surface of the feeder, substantially as described.

2. In a fountain-pen, a feeder provided with basins for the reception of ink, said basins being connected by grooves, the point of the feeder adapted for engagement with the nib 115 of the pen being apertured, as and for the purpose specified.

3. In a fountain-pen, a feeder comprising a body and a shank of less diameter than the body, the body having a tapering form and 120 provided with top and bottom basins, corresponding basins at the top and bottom being connected, as and for the purpose specified.

4. A feeder for fountain-pens, of tapering shape and provided with basins at top and 125 bottom, grooves connecting the basins at the top, and openings passing through the basin portions of the feeder from top to bottom, as and for the purpose specified.

5. A feeder for fountain-pens, provided 130 with series of basins at the top and at the bottom, sundry of the basins at top and bot-

tom being in registry, and all of the basins having openings made therein, extending through from top to bottom, and the feeder being further provided with a series of longitudinally-located grooves, as and for the purpose specified.

6. A feeder for fountain-pens, provided with basins at top and bottom and openings extending through the basin portions of the 10 feeder, the said feeder being provided with a shank of less diameter than the basin portion, and a collar loosely mounted on the said shank, as and for the purpose specified.

7. A feeder for fountain-pens, provided 15 with basins at top and bottom and openings extending through the basin portions of the feeder, the said feeder being provided with a shank of less diameter than the basin portion, and a collar loosely mounted on the said 20 shank, together with a fixed collar adapted at predetermined times to shut off the supply of ink from the barrel of the pen to the feeder when the feeder is connected with the barrel, as and for the purpose specified.

25 8. In a fountain-pen, the combination, with a barrel having an exit-opening for the ink, and a nozzle adjustably connected with the barrel, of a nib carried by the said nozzle, a feeder the body of which is located in the 30 nozzle, the body portion of which feeder extends along the bottom of the nib practically in engagement therewith, the said body being provided with upper and lower connected basins, and means, substantially as described, 35 for supplying ink from the barrel to the feeder, as and for the purpose set forth.

9. In a fountain-pen, the combination, with a barrel, a nozzle adjustable in the barrel, the said barrel being provided with an outlet 40 for the ink in communication with the nozzle, of a nib located in the said nozzle, a feeder the body of which is secured within the nozzle, the said feeder having top and bottom basins and apertures connecting the 45 same, the apertures extending to the point of the feeder which is adapted for engagement with the aforesaid nib, the feeder being provided with a shank extending loosely through the outlet of the barrel and into the barrel, 50 and a sliding collar mounted on the shank of the feeder, as and for the purpose specified.

10. In a fountain-pen, the combination, with a barrel, and a nozzle adjustable in the barrel, the said barrel being provided with an 55 outlet for the ink in communication with the nozzle, of a nib located in the said nozzle, a feeder the body of which is secured within the nozzle, the said feeder having top and bottom basins and apertures connecting the 60 same, the apertures extending to the point of the feeder which is adapted for engagement with the aforesaid nib, the feeder being provided with a shank extending loosely through the outlet of the barrel and into the barrel, 65 and a sliding collar mounted on the shank of the feeder, the inner end of the shank of said feeder being arranged to close or par-

tially close the outlet of the said valve, as and for the purpose specified.

11. In a fountain-pen, the combination, with 70 a barrel, and a nozzle adjustable in the barrel and adapted to receive a nib, of a feeder carried by the nozzle, having communicating top and bottom basins for the reception of ink and openings for the circulation of air, 75 the said feeder being provided with a valve at one end adapted in the adjustment of the nozzle to close the ink-outlet in the barrel of the pen, as and for the purpose specified.

12. In a fountain-pen, the combination, with 80 a barrel and a nozzle adjustable in the barrel and adapted to receive a nib, of a feeder carried by the nozzle, having basins for the reception of ink and openings for the circulation of air, the said feeder being provided 85 with a valve at one end, adapted in the adjustment of the nozzle to close the ink-outlet in the barrel of the pen, and a collar mounted to slide on the said feeder, between the basin portion thereof and the aforesaid valve, the 90 collar serving to force the ink to the outer extremity of the feeder, substantially as set forth.

13. In a fountain-pen, the combination with a barrel having an apertured partition, of a 95 sliding feeder having its inner end projecting through the said partition and provided with an enlargement or head for closing the aperture thereof, said feeder being provided with cavities, longitudinal grooves, and passages 100 for conducting the ink from the lower to the upper surface of the feeder, and a nozzle fitting tightly on the feeder over the cavities and movable with the feeder, substantially as shown and described.

105 14. In a fountain-pen, the combination with a barrel having an apertured partition, of a feeder having an enlargement or head at its inner end for closing the aperture of the said partition, said feeder having cavities on opposite sides connected by transverse apertures and provided with longitudinal grooves, and a nozzle fitting tightly on the feeder over the cavities and connected with the barrel to have endwise movement, whereby the 110 115 feeder can be slid in and out, substantially as and for the purpose set forth.

15. In a fountain-pen, the combination with a barrel, and a hollow plug fitting in the end of the barrel and having the bore of its inner 120 end reduced, of a feeder having an enlargement or head at its inner end for closing the inner end of the plug and provided with cavities in opposite sides connected by apertures and with longitudinal passages, and a nozzle 125 fitting tightly on the feeder over the cavities thereof and connected with the plug to have endwise movement therein, substantially as shown and described.
